(57) **CLAIM**

The ornamental design for a disc player, as shown and described.

DESCRIPTION

FIG. 1 is a top, front, and right side perspective view of a disc player showing our new design;

FIG. 2 is a front elevational view thereof;

FIG. 3 is a rear elevational view thereof;

FIG. 4 is a left-side, elevational view thereof;

FIG. 5 is a right-side, elevational view thereof;

FIG. 6 is a top plan view thereof;

FIG. 7 is a bottom plan view thereof; and,

FIG. 8 is a top, front, and right-side perspective view, showing the article with a lid thereof rotated away to an open position.

The broken lines are shown for the intended use of environment and form no part of the claimed design.
